The ornamental design for a mobile phone/video camera mount, as shown and described.

DESCRIPTION

FIG. 1 is a front perspective view of the mobile phone/video camera mount of the present invention showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side view thereof; and,

FIG. 7 is right side view thereof.

The broken lines depict environmental structure and form no part of the claimed design.

The broken lines on the carrier pouch represent stitching.
